Primary Examiner — Leanne Was-Englehart*Assistant Examiner* — Yelizaveta Y Masalimova(74) *Attorney, Agent, or Firm* — Banner & Witcoff, Ltd.(57) **CLAIM**

The ornamental design for a shoe as shown and described.

DESCRIPTION

FIG. 1 is a bottom photographic view of a shoe showing my new design;

FIG. 2 is a bottom front perspective photographic view thereof; and,

FIG. 3 is a bottom rear perspective photographic view thereof.

The broken lines and the greyed out area there within form no part of the claimed design. The remainder of the shoe shown in a greyed out photographic depiction forms no part of the claimed design.

1 Claim, 3 Drawing Sheets(56)
